ATTORNEY

UNITED STATES PATENT OFFICE.

CLAYTON P. SMITH, OF IOWA CITY, IOWA.

INTAKE-MANIFOLD.

1,305,174.

Specification of Letters Patent. Patented May 27, 1919.

Original application filed January 26, 1917, Serial No. 144,706. Divided and this application filed May 2, 1918. Serial No. 232,050.

To all whom it may concern:

Be it known that I, CLAYTON P. SMITH, a citizen of the United States, residing at Iowa City, in the county of Johnson and 5 State of Iowa, have invented certain new and useful Improvements in Intake-Manifolds, of which the following is a specification.

This invention relates to certain new and 10 useful improvements in charge mixing and vaporizing attachments for internal combustion engines and is a division of my co-pending application Serial #144,706, filed Jan. 26, 1917.

15 The primary object of the invention is to provide in a device of the character described, a manifold constructed in such a manner that the charge passing therethrough will be thoroughly mixed and vaporized before being admitted into the engine cylinder; thus insuring the introduction of a proper and uniform mixture into 20 all of the cylinders and preventing the premature fouling of the spark plugs of certain 25 of the cylinders by the introduction therein of an excessively rich mixture in proportion to the mixtures introduced into the remaining cylinders.

Another object of the invention is to so 30 construct the manifold that the cost of producing the same will be but slightly higher than the cost of the manifolds now in use, and which present such advantages as will 35 more than compensate for this slightly increased cost.

A still further object of the invention resides in the provision of a mixing device of 40 this character, the principles of which are applicable wherever a mixing or vaporizing attachment for gaseous fuel charges may be used.

Other objects of the invention as well as the specific details of construction and arrangement thereof will be more readily understood from the following description and accompanying drawings, in which:—

Figure 1 is a view, partly in section and partly in elevation illustrating a manifold constructed in accordance with the principles of my invention.

Fig. 2 is a transverse sectional view on the line 2—2 of Fig. 1.

Fig. 3 is an end elevation of the lower portion of the manifold in detached position.

55 The manifold indicated at 1, is of the

usual T configuration commonly employed in connection with gasoline motors, and its stem is provided at its lower end with a horizontally disposed portion 2 as is usual with devices of this character.

My invention resides in providing the manifold with a plurality of spaced ribs 3 which are preferably formed integral with the inner wall of the manifold substantially as shown in Figs. 1 and 2. These ribs have their inception at the open extremity of the horizontal portion 2, and extends substantially in spaced parallelism with one another to the point where the horizontal portion 2 is connected with the vertical portion or stem of the T-shaped manifold 1. Here the ribs 3 are bent to extend upwardly and spirally along the inner wall of said stem in spaced relation to one another substantially as shown in Fig. 1. By this arrangement, the mixing of the charge admitted into the manifold does not begin until the said charge has passed beyond the horizontal portion 2 and is about to pass upwardly through the stem—hence there is no resistance offered to the entrance of the charge at the open extremity of the horizontal portion 2, as would be the case if the ribs were spirally twisted throughout their entire length. These ribs have a tendency to retard the passage of the charge through the intake manifold while imparting helical movement thereto, and consequently by having the helically twisted portion of the rib spaced from the inlet end of the manifold, this retarding of the passage of the charge will not have any effect upon the admission of the fuel from the carburetor.

In practice, the charge admitted in the carburetor feed pipe designated at 4, is freely admitted into the horizontal portion 2 of the manifold. As this charge begins to ascend the stem, however, the spirally twisted ribs extending along the inner wall of this portion will impart a whirling movement to the charge and will thus insure a proper mixture and vaporization of the same before admission into the engine cylinder. In this manner each cylinder of the engine will receive a charge of exactly the same mixture as that received by the remaining cylinders, and consequently the premature fouling of the spark plug of any one cylinder will be prevented. It is pointed out in this connection that, in the usual

manifold, the charge is admitted to the cylinders in such a way that the first cylinder receives the richest mixture and consequently the spark plug of this cylinder is 5 frequently fouled by the deposits of carbon upon the contact points thereof. The present invention overcomes such an objection as set forth above.

Having thus fully described my invention 10 what I claim as new and desire to secure by Letters Patent, is:—

The herein described intake manifold of T-shape whose stem has a horizontal extension at its lower end communicating with 15 the mixture inlet pipe, and a plurality of

spaced ribs projecting from the wall into said extension and running parallel with each other and straight throughout the length of said extension, then bent at the angle between said extension and the stem 20 of the structure and carried upwardly in said stem, and disposed spirally throughout the length of the latter.

In testimony whereof I affix my signature in presence of two witnesses.

CLAYTON P. SMITH.
